UNITED STATES PATENT OFFICE

157,184

TABLE

George U. Nisle, Chicago, Ill.

Application June 18, 1948, Serial No. 147,042

Term of patent 7 years

(Cl. D33—14)

To all whom it may concern:

Be it known that I, George U. Nisle, a citizen of the United States, residing at Chicago, in the county of Cook and State of Illinois, have invented a new, original, and ornamental Design for Tables, of which the following is a specification, reference being had to the accompanying drawing, forming part thereof.

Fig. 1 is a perspective view of a table, showing my new design; and

Fig. 2 is a side elevational view.

I claim:

The ornamental design for a table, as shown.
